UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

WIRE TIE.

1,158,957.

Specification of Letters Patent.

Patented Nov. 2, 1915.

Application filed November 28, 1913. Serial No. 803,615.

To all whom it may concern:

Be it known that I, ADELMER M. BATES, a citizen of the United States, residing at Chicago, in the county of Cook and State of Illinois, have invented a certain new and useful Improvement in Wire Ties, of which the following is a specification.

My invention relates to metal ties for various purposes and its principal object is to obliterate or minimize the effects of the irregularities and projections commonly incident to the manufacture of such ties and to particularly prevent the rusting and deterioration of the ends of such ties and also to prevent their injury to the person of the user or the object with which they come in contact, and to minimize the amount of metal required to make the tie and to cause the tie when finally used to remain twisted, and to adhere to the object with which it is used.

The ties in question are usually formed from short lengths of wire, being cut from a reel and shaped or ended up in some predetermined manner. These ties are relatively small and must be handled with a good deal of speed, and if they have little sharp projections or roughened surfaces or points or edges, the hand of the operator is certain to be injured.

My invention is illustrated in the accompanying drawings, wherein—

Figure 1 is a side elevation of a tie with up-set ends; Fig. 2 is a side elevation of a tie with the ends and portions of the tie adjacent thereto coated; Fig. 3 is a side elevation of a tie, the ends of which are formed by minute loops; Fig. 4 is a side elevation of the same with the loops and the entire body of the tie coated; Fig. 5 is a side elevation of a tie having an enlarged loop at its ends; Fig. 6 is a side elevation of the same with one loop enlargement and a portion of the tie adjacent thereto coated, and the enlargement at the other end coated by way of modification.

Like parts are indicated by the same letters in all the figures.

A is the body of a tie. It may have the up-set ends B, B, or the minutely looped ends C, C, or ends terminating in large ends D, D.

E is a somewhat globular mass of adhesive material surrounding the up-set ends and carried back at F so as to coat a portion of

the end of the tie adjacent to one enlargement.

G, G are similar masses of adhesive material inclosing the minute loops.

H is a sheath of the same or similar material which coats the entire body of the tie.

J is a mass of such adhesive material inclosing the enlargement of the tie which is formed with two large loops at its ends. K is a similar coating surrounding one of these loops and L is a similar coating acting as a sheath for one end of the tie near one of the loops.

I have endeavored in this manner to show modifications and variations. The adhesive material which as hereinafter explained may be of any desired substance as solder or glue but which is preferably made of a glue-like substance, can be used to inclose the ends or the roughened portions of the tie or to inclose the end and a portion of the tie near such end, that is the portion which is to form the twist, or to inclose the entire body or to inclose the loop if a loop is formed, and the two ends of any given tie or set of ties could be differently treated if that should be found desirable. I do not therefore wish to be limited to the particular size, form, proportions and relations of the ends or the coatings used or the materials of which the coatings are made, and it might be found desirable to use one material for the roughened portion and one for the body of the tie or the loop, and it might be found desirable to use one kind of material at one end of the tie and another kind at the other end to get a better adhesive or locking effect when the two ends are twisted together.

The ties are required to have some kind of an enlarged end so that they can be held by a tool, for their ends commonly have to be overlapped so as to draw the body of the tie about the object to be tied and then they are twisted to tighten the tie on such object.

The tie of my invention is thus formed with the upset ends, the small loops or the large loops or otherwise as may be convenient and desirable. These roughened ends or roughened portions of the ends are now dipped or in any other manner coated with a liquid which subsequently penetrates the interstices and ultimately partially hardens so as to leave a smooth, somewhat globular body about and inclosing the roughened or enlarged portions. Various kinds of

glue or glue-like materials can be employed, preferably having for their base either tar, pitch or asphaltum substances. Broadly speaking, the preferred idea is to use a substance which will flow about the enlargement, fill the interstices, form a more or less globular protection about and inclosing the enlarged end or enlargement on the end as the case may be, set or harden sufficiently to 5 prevent its being easily broken or separated from the tie, protect the fingers of the user or the materials with which it comes in contact and tend to adhere to such material so as to keep the tie in place. This coating may 10 also be of solder but in this event there is more than the necessary trouble and expense because the wire must be acid cleaned. A glue-like substance which dries readily is preferable, and into a mass of the same the 15 part to be treated is immersed. The irregularities or projections on the part to be treated tend to cause such liquid to gather in a more or less globular mass about such part and there to remain, filling the interstices 20 and forming a relatively smooth or globular exterior. If, as I prefer, such adhesive material is carried back along the surface of the tie for a considerable distance from one or both of the enlarged ends it will tend when 25 30 these two parts are twisted together to tighten the tie about the object to prevent them from untwisting and requires less wire because less wire twists are necessary. The

result, when a tie so made with adhesive material is finished and tightened in position, 35 is to give a twisted tightened end which is protected by such adhesive material against rust and deterioration, and is rendered incapable of injuring the person of the operator or the material with which it comes in 40 contact and which tends to adhere to such material so as to hold the tie in place.

I claim:

1. A tie comprising a wire body having enlargements on its ends and a mass of adhesive material surrounding each enlargement. 45
2. A tie comprising a wire body having enlargements on its ends and a mass of adhesive material surrounding each enlargement and a considerable portion of said wire body 50 adjacent said enlargement.
3. A tie comprising a wire body having looped ends and a mass of adhesive material surrounding each end.
4. A tie comprising a wire body having 55 looped ends and a mass of adhesive material surrounding each end and a considerable portion of said wire body adjacent said looped end.

In testimony whereof, I affix my signature 60 in the presence of two witnesses this 22nd day of November 1913.

ADELMER M. BATES.
